DISPLAY STAND

Alfred D. Mosby, Moline, Ill., assignor, by mesne assignments, to American Machine & Metals, Inc., New York, N. Y., a corporation of Delaware

Application June 15, 1935, Serial No. 26,762

5 Claims. (Cl. 40—125)

This invention relates to display racks. It is an object of this invention to provide a bill poster of economical and efficient construction in which the materials to be displayed may be inserted and removed without tearing and which nevertheless may be held in a taut position to present a good appearance. It is a further object to provide a display rack in which bill posters or the like may be held for display without need 10 for employing any adhesive. Another object is to provide an object of the character described which may be manufactured economically and which may be manipulated with ease.

Other objects will be in part obvious and in 15 part appear hereinafter.

The invention accordingly comprises an article of manufacture possessing the features, properties, and the relation of elements which will be exemplified in the article hereinafter described 20 and the scope of the application of which will be indicated in the claims.

For a fuller understanding of the nature and objects of the invention, reference should be had to the following detailed description, taken in 25 connection with the accompanying drawing, in which:

Fig. 1 is a front elevation of a device embodying this invention.

Fig. 2 is a side elevation thereof.

30 Fig. 3 is a front elevation of the removable frame by which the display material is held in place.

Fig. 4 is a side elevation thereof.

35 Fig. 5 is a perspective view of the device during the process of inserting the display material.

Fig. 6 is a perspective view of a modification of the device.

Fig. 7 is a section along the lines 7—7 of Fig. 1.

40 Fig. 8 is a fragmental view showing the locking arrangement.

In the drawing the numerals 10—10 represent two substantially rectangular frames pivoted together at 11 and having feet 12—12. A strap 13 extending from one frame 10 to the other, braces 45 the frames 10 at a proper distance to form a triangular stand in the usual manner.

The members 10 are substantially alike and one only need be described.

Mounted upon the frame is a flat rectangular 50 sheet 14, having each of its ends 15 bent backwardly upon itself to form a U-shaped recess 16.

A rectangular frame comprising side bars 17, and end bars 18, to hold the display material, (which for convenience may be referred to as a poster) in 55 place.

These side members 17 are both elastically flexible and the end members 18 are very much smaller in thickness than the width of the recess 16, and are so placed on the members 17 that when the lower member 18 is within the lower recess 16, the upper member 18 reaches substantially to the top of the upper recess 16.

The side members 17 are preferably bowed inwardly as shown in Fig. 4, so that when the upper and lower ends 18 are confined within their respective recesses 16, the side members 17 will bear resiliently against the sides of the poster to hold it in place.

When the side members are bowed as shown in Fig. 4, it is not necessary to provide any retaining means to hold the parts in place but when such means are desired there may be provided upon the center of each side bar 17 a latch 19 pivoted at 20 and having a projection 21 adapted to fit within a hole 22 in the sides of the frame 10. 20

I have found in the manufacture of display racks of this type that the recesses 16 must be much wider than the thickness of the bars 18 to afford a substantial clearance in order that when the rectangular frame is being inserted in 25 place, the ends of the poster may, if necessary, slip around the ends of the frame after the poster has become taut to prevent the poster tearing at that point.

In using the device, the frame work 10 is set in 30 position and the poster is laid over the rectangular member 14 in substantially its final position. Thereupon one end 18 of the removable frame is inserted into its recess in either top or bottom, whichever is the more convenient, carrying the ends of the poster with it and holding it in place. The center of the rectangular frame may now be bowed outwardly against its own resilience, and the other end member 18, with the free end of the poster bent over, it may be 35 snapped into the other recess.

During the initial portion of this motion, the poster is stretched over the surface 14. As soon, however, as the poster is taut the remaining motion of the member 18 is accompanied by a slipping of the end of the poster around the end bar 18. In this manner, the poster is quickly and easily tightened into place without danger of tearing. When the rectangular frame has been put in place, the latches 19 may be closed to 40 fasten it there.

In the embodiment shown in Fig. 6, the side bars 17 of the rectangular frame are bowed outwardly at the center so that both ends 18 of the frame may bear against the poster; thus as the 45 50 55

center is pressed inwardly and locked by the latches 19, the poster is stretched and held taut.

Since certain changes may be made in the above construction and different embodiments 5 of the invention could be made without departing from the scope thereof, it is intended that all matter contained in the above description or shown in the accompanying drawing shall be interpreted as illustrative and not in a limiting 10 sense.

It is also to be understood that the following claims are intended to cover all of the generic and specific features of the invention herein described, and all statements of the scope of the 15 invention which, as a matter of language, might be said to fall therebetween.

What I claim and desire to secure by Letters Patent is:

1. A display rack comprising in combination a 20 rectangular frame, a backing material upon said rectangular frame, longitudinal recesses at opposite sides of said backing material, and a frame work for holding display material within said recesses, comprising end bars of a thickness materially less than the width of said recesses, and side bars of resilient material, and bowed outwardly at the ends, whereby when the display material is inserted in the frame said side bars 25 will bear resiliently upon the sides of said posters when the end bars are held within said recesses.

2. A display rack comprising in combination a rectangular frame, a backing material upon said rectangular frame, longitudinal recesses at 30 opposite sides of said backing material, and a frame work for holding display material within said recesses, comprising end bars of a thickness materially less than the width of said recesses, and side bars of resilient material, and centrally disposed latches in said 35 side bars.

3. A display stand consisting of a pair of display racks hinged together at their tops, a flat rectangular member adapted to receive a poster attached to each of said racks and having its ends bent back upon itself to form recesses upon the front side, a frame work comprising end bars and side bars connected to said end bars and adapted to space said end bars causing them to fit within said recesses, said recesses being materially wider than the thickness of the end bars 10 on the frame, whereby when a paper poster is inserted within the recess by means of the end bars it may slip around the end of the end bars without tearing the paper.

4. A display stand consisting of a pair of display racks hinged together at their tops, each comprising in combination a rectangular frame, a backing material upon said rectangular frame, longitudinal recesses at opposite sides of said backing material, and a frame work for holding display material within said recesses, comprising end bars of a thickness materially less than the width of said recesses, and side bars of resilient material, and bowed outwardly at the ends, whereby when the display material is inserted in the frame said side bars will bear resiliently upon the sides of said posters when the end bars are held within said recesses.

5. A display stand consisting of a pair of display racks hinged together at their tops, each comprising in combination a rectangular frame, a backing material upon said rectangular frame, longitudinal recesses at opposite sides of said backing material, and a frame work for holding display material within said recesses, comprising end bars of a thickness materially less than the width of said recesses, and side bars of resilient material, and centrally disposed latches in said side bars.
